DESIGN FOR CENTER-PIECE.

Design No. **11,234**, dated June 10, 1879

UNITED STATES PATENT OFFICE.

SAMUEL KELLETT, OF SAN FRANCISCO, CALIFORNIA.

DESIGN FOR CENTER-PIECE.

Specification forming part of Design No. **11,234**, dated June 10, 1879; application filed March 6, 1879.
[Term of patent 7 years.]

To all whom it may concern:

Be it known that I, SAMUEL KELLETT, of the city and county of San Francisco, State of California, have invented and produced a new and original Design for a Center-Piece, of which the following is a specification.

My design is illustrated in the accompanying photograph, and by letters marked thereon, which represents a face view of design.

The interior of design is inclosed by bead-molding, and is composed of forms scrolled at exterior ends. From middle of scrolls clusters of fruit and flowers extend toward drop of center-piece. The middle portion of design is a wreath of stems, leaves, and berries on plain ground between bead-molding and fillet on outer edge of wreath. This fillet is turned into scrolls at intervals, throwing out stems

and shell-like leaf. The exterior edging is irregular, turning into scrolls at sides of leaf. A shield fills space between last-described figures, completing outside finish of design.

The letter A indicates forms with fruit and flowers, forming inner portion of design; B, wreath of stems, leaves, and berries; C, fillet; D, shell-like leaf; E, exterior edging; F, shield between leaves.

What I claim as new, and desire to secure by Letters Patent, is—

The design for center-piece, as shown and described.

SAML. KELLETT.
